UNITED STATES PATENT OFFICE.

EDWARD L. GILLESPIE, OF SEATTLE, WASHINGTON.

DISAPPEARING WALL-BED.

1,016,139.

Specification of Letters Patent.

Patented Jan. 30, 1912.

Application filed March 23, 1911. Serial No. 616,533.

To all whom it may concern:

Be it known that I, EDWARD L. GILLESPIE, citizen of the United States, residing at Seattle, in the county of King and State of Washington, have invented certain new and useful Improvements in Disappearing Wall-Beds, of which the following is a specification.

This invention relates to improvements in disappearing wall-beds.

The principal object of the invention is the provision of a folding bed of simple construction that may be conveniently mounted in a wall-closet or alcove to occupy the least amount of space practicable.

Another object of the invention is the provision of means for pivotally mounting the bed with supplementary counterbalancing devices that allow the same to be easily operated and which will reliably maintain the bed in its upright position when not in use.

A further object of the invention is the disposition of the said counterbalancing and other mechanism that they may not be visible and obtrusive in appearance when the bed is open or closed.

With the aforementioned and other objects in view as will appear in the further description, the invention consists in the novel construction and arrangement of a disappearing wall-bed and the combination and adaptation therewith of devices, as will be hereinafter described and claimed with reference to the accompanying drawings, wherein—

Figure 1 is a longitudinal sectional view of apparatus embodying my invention, shown in open condition. Fig. 2 is a like view of the same, in closed condition. Fig. 3 is a front view in cross section through 3—3 of Fig. 1. Fig. 4 is a fragmentary cross sectional view through 4—4 of Fig. 1.

The following described devices are, unless otherwise specified, in duplicate and positioned in similar relative positions upon each side of the bed. One side only is described to avoid repetition and unnecessarily involved description.

The reference numeral 1 designates the frame of a wall closet adapted to receive the bed apparatus in upright condition when the same is closed. 2 is an upright post upon each side of said closet secured at top and bottom in sockets 3 and having a transversely disposed tubular bar 4 mounted therein at its respective ends, and whereat

the said posts may be suitably braced to the side walls of said closet, as at 5. A bed frame is pivotally connected to said bar and comprises the rectangular frame 6, the front legs 7 and the fixed head-and-foot boards 8 and 9, respectively. 10 is an angularly disposed brace having one end secured to the side rail of said frame and its other end offset from the vertical plane of the side rails of said frame, and rigidly connected to the projecting end of a transverse rod 11 of said head-board. The former end of each said brace may desirably terminate in a rectangularly directed block 12 provided with a plane upper surface for close engagement with the lower surface of said side rail and an arc-shaped depression 13 arranged to be seated on the tubular bar 4. Said pivotal connections are afforded through the utilization of a U-shaped threaded bolt 14 which embraces said bar and is passed through apertures in the block and in the bottom flange of the respective side rail whereat it is fixedly secured by nuts 15.

A set collar 16 is provided on each post and a slidable collar 17 therebelow between which is positioned a helical spring 18 which serves to urge the collar 17 downwardly. Oppositely directed pins 19 on the latter collar afford pivotal connections with links 20 whose lower ends are similarly connected at 10' upon opposite sides to the upper portion of the brace 10. The amount of tension in the spring 18 may be varied by the vertical adjustment of the set collar 16, as by a cotter-pin 21 which may be selectively positioned in spaced holes 22 in said post.

23 is an extension of the head-board of the bed-frame which is hingedly connected thereto through the pivotal engagement of vertical end members 24 at each side thereof with the transverse rod 11. Said members may be flanged for fixedly securing same conveniently to a vertical panel 25. Said panel is provided with a pin 26 upon each of its opposite vertical sides and which projects into an arcuate slot 27 of a fixture 28 secured on the respective lateral walls of said closet and designed to guide the movements of upper portions of said panel.

When the bed is in its closed or inoperative condition, as shown in Fig. 2, the spring is extended and engaging with the collar 17 transmits its pressure through the links 20 to the brace 10. The leverage thus afforded from the fulcrum 4 will reliably support the

bed in upright position without other or extraneous means.

A moderate outward force applied on the upper portion or foot of the bed will cause 5 a powerful leverage to be exerted on said fulcrum in opposition to the power of said spring. As the bed is lowered the upwardly moving outer portions of the brace 10 describe an arc and carry therewith the links 10 20 which compress the spring 18 through the instrumentality of the movable collar 17.

Furthermore, when the bed is in its lowest horizontal position, see Fig. 1, the said offset connection 10 is more nearly in 15 line with the force of said spring and which is thus brought into a position whereat the spring is rendered practically inoperative with respect to the connection 10. However, as the bed is raised by applying an upward 20 force to the foot thereof, said spring tension will urge the bed upwardly with increased effect until the same has reached its upright position.

In the depression of the head of the bed 25 when the same is folded into its closed or vertical position the head board extension 23 and the panel 25 to which it is fixedly secured are likewise drawn downwardly. The provision of the fixture 28 having an 30 arcuate slot which corresponds to the curve of the path taken by the pivotal connection of the members 24 with said rod 11 and in which the upper portion of said panel is mounted causes said panel to partake of the 35 upward and downward movements of said head and to be at all times in vertical positions.

The panel in its elevated position during 40 the lowering of the bed, as shown in Fig. 1, may desirably have its upper edge enter a recess 29 in the upper portion of said closet.

It will be particularly noted that the mechanism is simple in its construction and 45 convenient in operation; also that the working parts of the mechanism may be concealed from view as by the casing 30 of the closet.

The invention is especially adapted for 50 use where economy of space is an object such as in apartment houses and small cottages and where it is desirable to have a room serve a double purpose, at times being utilized as sleeping quarters.

Obviously, many changes may be made in detail and the general arrangement of the

structure as described but without departing 55 from the spirit of the invention and all such changes and modifications falling within the scope of the appended claims are contemplated in my present invention.

Having described my invention, what I 60 claim as new and desire to secure by Letters-Patent, is—

1. In apparatus of the class described, the combination of a pair of upright posts, a horizontal bar connecting said posts, a bed 65 frame pivotally mounted on said bar, a head board secured to the inner end of the frame, an inclined brace at each side between said head-board and the frame having its connection with said board outwardly offset 70 from the plane of its connection with the frame, a fixed and a movable collar provided on each post, a helical spring interposed between said collars, and link connections between said movable collar and said brace. 75

2. In apparatus of the class described, the combination of a pair of upright posts, a horizontal bar connecting said posts, a bed 80 frame pivotally mounted on said bar, a head-board secured to the inner end of the frame, an inclined brace at each side between said head-board and the frame affording a seat for the reception of said bar, a fixed and a movable collar provided on each post, a helical spring interposed between said collars, 85 and link connections between said movable collar and said brace.

3. In apparatus of the class described, the combination of a pair of upright posts, a horizontal bar connecting said posts, a bed 90 frame pivotally mounted on said bar, a head-board secured to the inner end of the frame, an inclined brace at each side between said head-board and said frame and having its connection with said board outwardly offset 95 from the plane of its connection with the frame, a fixed and a movable collar provided on each post, a helical spring interposed between said collars, link connections 100 between said movable collar and said brace, an extension pivotally connected to said head-board, and a panel fixedly secured to said extension.

EDWARD L. GILLESPIE.
